Primary Examiner — Brian N Vinson(74) *Attorney, Agent, or Firm* — Timothy H. Van Dyke; Beusse, Wolter, Sanks & Maire, P.A.(57) **CLAIM**

The ornamental design for a hanging corner shelf assembly, as shown and described.

DESCRIPTION

FIG. 1 is a top, front and left side perspective view of a hanging corner shelf assembly showing a first embodiment of design;

FIG. 2 is a front elevational view thereof;

FIG. 3 is a rear elevational view thereof;

FIG. 4 is a right side elevational view thereof;

FIG. 5 provides a top plan view thereof;

FIG. 6 is a bottom plan view thereof; and,

FIG. 7 is a top, front, and left side perspective view of a second embodiment thereof.

The broken-line disclosure is intended to represent portions of the assembly which form no part of the claimed design.
